UNITED STATES PATENT OFFICE

JOSEPH S. BELT, OF AMARILLO, TEXAS

HEAT EXCHANGER

Application filed July 26, 1932. Serial No. 624,836.

This invention relates to improvements in heat exchangers adapted for general use to cool or heat various fluids, either in liquid or gaseous form.

5 The primary object of the present invention is to provide an extremely simple and compact heat exchanger embodying a coil through which the fluid to be cooled or heated is adapted to be passed, a casing through 10 which the cooling or heating fluid is adapted to be passed in a direction countercurrent to the direction of flow of the fluid to be cooled or heated, and means to cause the cooling or 15 heating fluid to flow in a spiral path about and between the convolutions or spiral portions of the coil to afford a maximum cooling or heating surface.

A further and more specific object of the invention is to provide a heat exchanger of the 20 above character wherein the parts are so constructed and related as to facilitate assembly thereof, as well as to facilitate access to and removal of the coil for renewal or repair.

The invention consists in the novel form, 25 combination and arrangement of parts hereinafter more fully described, shown in the accompanying drawings and claimed.

In the drawings:

30 Figure 1 is a view partly in side elevation and partly in central longitudinal section, of a heat exchanger embodying the present invention.

Figure 2 is a transverse section on line 2—2 of Figure 1.

35 Figure 3 is a view similar to Figure 1, of a modified form of the invention; and

Figure 4 is a transverse section on line 4—4 of Figure 3.

40 Referring in detail to the drawings, the present invention constitutes a heat exchanger of the countercurrent or counterflow type including a casing composed of a tubular body 5 having end flanges 6 and closed at the ends by cover plates 7 bolted as at 8 to said flanges. On the inner surface of the casing body 5, I provide a spiral vane 9 to cause the cooling or heating medium to follow a spiral path in passing through the casing, the latter being provided near one end with 45 a tangential inlet 10 and near the other end

with a tangential outlet 11 for the cooling or heating medium, whereby the spiral flow of the latter is facilitated.

Arranged within and axially of the casing 55 is a coil 12 arranged wholly within the confines of the spiral vane 9 so as to be readily inserted or withdrawn from the casing during assembly or when making repairs. The fluid to be cooled or heated is adapted to be passed through the coil 12, and it will be seen 60 that the cooling or heating medium will be caused to flow past as well as between and in the general direction of the windings of the coil so as to afford a maximum heating 65 or cooling surface. While a single helical coil is illustrated in Figure 1, it is obvious that the number of coils may be increased in any of several known different relations. The coil has straight end portions, and the cover 70 plates 7 are provided with stuffing boxes 13 through which these straight end portions pass, whereby leakage of the cooling or heating medium from the casing about the ends of the coil where they pass through the cover 75 plates 7 is prevented.

A core 14 is preferably removably positioned axially of and within the coil 12 and provided with an external spiral vane 15 corresponding in pitch and direction to the vane 9 of the casing. Obviously, the vane 15 will 80 cooperate with vane 9 to more efficiently induce the spiral flow of the cooling or heating medium in the casing. However, by having these vanes separate and in spaced relation with the coil 12 removably disposed 85 therebetween, assembly and removal of the parts for repair may be expeditiously and cheaply accomplished. The core 14 may be supported in position in any desired manner, but as shown it has its ends arranged in and 90 supported by sockets 16 provided on the inner surfaces of the cover plates 7. The end 17 of the coil 12 constitutes its inlet end, while the end 18 thereof constitutes its outlet end, as will be apparent.

95 The construction of Figures 1 and 3 is substantially the same, the principal difference being in the form of the coil 12. In the embodiment of Figure 3, the coil 12 consists of a series of spaced spiral portions 19 al- 100

ternately wound from outside to center and center to outside to avoid the use of a multiplicity of coils where greater cooling or heating surface is desired for the coil than 5 may be had by the use of a simple helical coil in a heat exchanger of given size. The number of spiral portions 19 is preferably not more than twice the number of convolutions of the vane 9, and the portions 19 are preferably spaced apart a distance less than the 10 distance between adjacent convolutions of said vane 9 so that intimate contact of the cooling or heating medium with the surfaces of all of the spiral portions 19 will be had. 15 The coil 12 of the embodiment of Figure 3 will be comparatively rigid and strong so as to present little probability of sagging of the coil when the heat exchanger is used in a horizontal position as shown. However, 20 when the heat exchanger is used in a vertical position, it will probably be necessary to support the individual spiral portions 19, and for this purpose the core 14 is provided at intervals with transverse openings 20 be- 25 tween the connected inner end portions of adjacent pairs of the spiral portions 19, so that supporting rods may be passed through these openings to sustain the weight of the portions 19 and retain them in their proper 30 flatly spiraled condition.

From the arrows in Figures 1 and 3, and those of Figures 2 and 4, it will be seen that the heating or cooling medium enters the casing through the inlet 10 with an initial 35 whirling movement between the convolutions of the vane 9 at the adjacent end of the casing, such medium then flowing around the spiral portions or convolutions of the coil 12 in a spiral path defined by the vane 9 and 40 the vane 15. It will be further seen that the flow of the cooling or heating medium through the casing is in a general direction opposite or counter to the flow of fluid to be cooled or heated passing through the coil 12. 45 The flow area of the cooling or heating medium is sufficiently large to permit it to pass rapidly through the spiral path, and the exposed surfaces of the coil will rapidly exchange the heat. 50 While I have described embodiments of the invention which are at present believed to be preferred, it is to be understood that minor changes are contemplated within the spirit and scope of the invention as claimed.

55 What I claim as new is:

1. A heat exchanger including a casing composed of a body and removable end closure plates, said body having a spiral vane on the inner surface thereof, said casing having 60 an inlet at one end and an outlet at the other end for a cooling or heating medium, and a coil removably arranged axially of the casing wholly within the confines of said vane and having inlet and outlet ends passing through 65 said end closure plates to facilitate flow of

a fluid to be cooled or heated therethrough countercurrent to the flow of the cooling or heating medium through the casing.

2. A heat exchanger including a casing composed of a body and removable end closure plates, said body having a spiral vane on the inner surface thereof, said casing having an inlet at one end and an outlet at the other end for a cooling or heating medium, a coil removably arranged axially of the casing wholly within the confines of said vane and having inlet and outlet ends passing through said end closure plates to facilitate flow of a fluid to be cooled or heated therethrough countercurrent to the flow of the cooling or heating medium through the casing, and stuffing boxes on said end closure plates through which said ends of the coil pass.

3. A heat exchanger including a casing composed of a body and removable end closure plates, said body having a spiral vane on the inner surface thereof, said casing having an inlet at one end and an outlet at the other end for a cooling or heating medium, and a coil removably arranged axially of the casing wholly within the confines of said vane and having inlet and outlet ends passing through said end closure plates to facilitate flow of a fluid to be cooled or heated therethrough countercurrent to the flow of the cooling or heating medium through the casing, said inlet and outlet of the casing opening through the opposite ends of the casing body tangentially of the latter for cooperation with the spiral vane to facilitate flow of the cooling or heating medium in a spiral path between the coil portions of the coil.

4. A heat exchanger including a casing composed of a body and removable end closure plates, said body having a spiral vane on the inner surface thereof, said casing having an inlet at one end and an outlet at the other end for a cooling or heating medium, a coil removably arranged axially of the casing wholly within the confines of said vane and having inlet and outlet ends passing through said end closure plates to facilitate flow of a fluid to be cooled or heated therethrough countercurrent to the flow of the cooling or heating medium through the casing, and a core removably arranged axially of the casing within the coil and having an external spiral vane corresponding in pitch and direction substantially to that of the 110 vane on the inner surface of the casing body.

5. A heat exchanger including a casing composed of a body and removable end closure plates, said body having a spiral vane on the inner surface thereof, said casing having an inlet at one end and an outlet at the other end for a cooling or heating medium, a coil removably arranged axially of the casing wholly within the confines of said vane and having inlet and outlet ends passing

through said end closure plates to facilitate flow of a fluid to be cooled or heated there-through countercurrent to the flow of the cooling or heating medium through the casing, and a core removably arranged axially of the casing within the coil and having an external spiral vane corresponding in pitch and direction substantially to that of the vane on the inner surface of the casing body,
5 said coil having a series of spaced flat spiral portions alternately wound from outside to center and from center to outside so that said spiral portions are connected in communication with each other in pairs at the center,
10 said core having transverse openings at intervals and at points between the connections between the centers of said pairs of spiral portions of the coil, whereby support of the pairs of spiral coil portions may be facilitated
15 when the heat exchanger is used in a vertical position.
20

In testimony whereof I affix my signature.

JOSEPH S. BELT.
